2 Sheets-Sheet 2

UNITED STATES PATENT OFFICE

HUGH G. BUCHAN, OF PHILADELPHIA, PENNSYLVANIA

ADDENDUM SHEET HOLDER

Application filed August 14, 1929. Serial No. 385,798.

This invention relates to a sheet holder which is adapted to be used in combination with a book or directory holder for securing additional sheets and maintaining them alongside of the book or directory.

The invention is especially adapted for telephone directory holders in that it will properly secure the additional directory sheets which are issued by telephone companies as new customers occur. These extra sheets are issued from time to time and there has always been more or less difficulty in keeping them with the directory. According to this invention these sheets are now anchored to the directory holder as they arrive and they occupy substantially the same position as the directory proper.

The invention comprises the novel structure and combinations of parts hereinafter described and more particularly pointed out and defined in the appended claims.

In the accompanying drawings which illustrate a preferred form of this invention and in which similar reference numerals refer to similar features in the different views:

Figure 1 is an interior plan view of a book holder embodying this invention illustrating in dotted lines the manner of assembling a book or directory with respect to the holder.

Figure 2 is a fragmentary perspective view of a book holder involving this invention.

Figure 3 is an enlarged broken interior plan view showing the back and compartment in section.

Figure 4 is an enlarged sectional view taken upon the line IV—IV of Figure 3.

Figure 5 is an enlarged sectional view taken upon the line V—V of Figure 3 with the addition of the loose sheet anchor.

Figure 6 is an enlarged broken side elevational view of the book holding compartment.

In connection with this invention, there is shown in the drawings a book or directory holder consisting of the side cover members 1 which are suitably connected by a back portion 2 as is usual in the art. The back portion 2 is preferably of a rigid nature for the purpose of supporting two sets of angle members 3 and 4 and 5 and 6 which are suitably

secured by one flange thereof to the back portion of the book holder. The vertical or upstanding flanges of the angle members 3 and 5 are in alignment and the upstanding flanges of the angle members 4 and 6 are likewise in alignment thereby providing a form of compartment for receiving the rear portion of a book or directory which is adapted to be contained within the holder. A pair of sockets 7 are formed in the back portion of the book holder as shown in Figure 3 and these sockets 7 extend through apertures in the attaching flanges of the angles 3 and 5 in the present instance. A loose sheet anchoring rail 8 which is provided with depending lugs 9 adapted to enter the sockets 7 is provided. This loose sheet anchor 8 is adapted for confining additional sheets alongside of the book or directory. These loose sheets are preferably provided with suitable apertures through which the lugs 9 extend as shown in Figure 5 with the result that the loose sheets 10 as illustrated in Figure 5 are firmly anchored by one margin below the anchor 8.

The outer ends of the angle members 5 and 6 are connected by a rod 11. The outer ends of the angle members 3 and 4 sustain a removable rod 12 which is shown in the form of a small tube. Resilient metal strips 13 are secured to the outer surfaces of the angle members 3 and 4 by means of keepers 14 which are struck outwardly from the upstanding flanges of the angle members 3 and 4 as shown in Figure 4. The outer end of each resilient strip 13 carries a pin 15 which is adapted to extend through an aperture in the upstanding flange of the supporting angles and into the rod 12 as shown in Figure 3. The transverse rods or posts 11 and 12 are adapted for sustaining one or more wire rods 16 as shown in Figure 1. These wire rods 16 are adapted for securing the book or directory within the holder. In order to assemble the book or directory with respect to the wire rods 16, the resilient members 13 will be pulled outwardly as shown in Figure 1 to release the post 12 whereby the wires may be swung upon the post 11 as a pivot into the position shown in dotted lines in Figure 1. When the wires 16 have been swung into the dotted line position

as shown in Figure 1, the book or directory is suspended thereon with the wires engaging between the leaves thereof as shown in Figure 2. The assembled book is then swung over 5 the cover and the pins 15 are again secured in the rods 12 whereby the book becomes firmly secured within its holder. It will be noted that the loose sheet anchor 8 will lie beneath the back of the book and will be held 10 in position thereby. Now when a telephone company furnishes additional sheets with subscribers thereon and it is desired to add the same to the directory in the event that the holder is used for a telephone directory, the 15 directory will be released and swung into the dotted line position shown in Figure 1. The loose sheet anchor will then be removed and applied to the loose sheets with the lugs 9 extending through the apertures in such 20 sheets. The sheet anchor 8 will then be replaced within the back of the directory-holding compartment with the lugs 9 extending through the apertures 7. The directory may then be swung back into its position while 25 the loose sheets as represented by the reference numeral 10 will be confined alongside of one of the covers of the directory.

From the foregoing it will be obvious that a 30 very expedient and novel means has been provided for securing additional sheets in a holder of the class described. It will be appreciated that these loose sheets may be added from time to time by simply removing the book or directory and placing such sheets 35 underneath the anchor 8.

I am aware that many changes may be 40 made and numerous details of construction may be varied through a wide range without departing from the principles of this invention, and I therefore do not purpose limiting the patent granted hereon otherwise than necessitated by the prior art.

I claim as my invention:

1. The combination with a book holder 45 having means for receiving and confining the rear part of a book, of a loose leaf anchor having means for engaging loose sheets and anchoring the same to the bottom of said holder.
2. The combination with a book holder 50 having a compartment for receiving the rear part of the book, means for confining said book within said compartment for swinging movement in an endwise direction, and a removable anchor for loose sheets adapted to be secured in the bottom of said compartment for the purpose set forth.
3. In a book holder having a compartment 55 for receiving the rear end of said book and a sheet holder removably secured in the bottom of said compartment for confining loose sheets.
4. The combination with a directory holder 60 having means for receiving the rear part of said directory, and means beneath the rear

end of said directory for confining loose sheets extending alongside of said directory.

5. In a directory holder having a compartment for receiving the rear part of said directory, said compartment having spaced 70 apertures, and a bar having prongs adapted for extending through loose sheets and extending into said apertures beneath the directory.

6. In a directory holder having a compartment for receiving the rear edge of said directory, a loose sheet holder extending lengthwise of the bottom of said compartment, said sheet holder and compartment having cooperating means for securing said holder in a predetermined position, and means for confining a directory within said compartment of said sheet holder.

In testimony whereof I have hereunto subscribed my name at Philadelphia, Philadelphia County, Pennsylvania.

HUGH G. BUCHAN.
